UNITED STATES PATENT OFFICE.

HENRY J. NOLTE, OF SCHENECTADY, NEW YORK, ASSIGNOR TO GENERAL ELECTRIC COMPANY, A CORPORATION OF NEW YORK.

ELECTRON-DISCHARGE DEVICE.

Original application filed February 7, 1921, Serial No. 443,005. Divided and this application filed September 18, 1923. Serial No. 663,470.

My present invention, which is a division of my prior application, Serial No. 443,005, filed February 7, 1921, relates to electron discharge devices, and more particularly to devices of the type employing at least three electrodes, comprising a cathode, an anode and a grid member for controlling the passage of an electron stream between cathode and anode.

10 The object of my invention is to provide an efficient and convenient method for removing occluded gas from the electrodes of such devices during the process of exhaust.

15 The novel features which I believe to be characteristic of my invention are set forth with particularity in the appended claims; the invention itself, however, will best be understood by reference to the following description taken in connection with the accompanying drawing in which Fig. 1 is a view partly in section of a device with which my invention may conveniently be employed; Fig. 2 is a view of the grid and the structure whereby it is supported; and

20 Figs. 3 and 4 are detail views of portions of the grid structure.

The device indicated in the drawing comprises an evacuated receptacle comprising a portion 1 of glass and a portion 2 of metal. The glass portion is sealed to the metal portion by means of a thin metal ring 3 which is preferably of copper or an alloy having substantially the same coefficient of expansion as the glass of which the part 1 is composed. This ring 3 is soldered or welded to the portion 2 and forms a gas-tight seal with the glass at the region 4 where it is surrounded by the glass wall of the portion 1. The filamentary cathode 5, which is preferably of tungsten is supported within the receptacle by means of supporting arms 6, 7 and 8, the arms 6 and 7 also serving as supply conductors of the cathode. The grid 15, which surrounds the cathode is in the form of a cylindrical screen made up of two sets of wires 16, 17, which are wound spirally in opposite directions and interwoven. By means of this construction the principal expansion of the grid when heated will occur in the direction of its diameter and the tendency of the grid to buckle and make contact with the filament or anode will be largely eliminated. The ends of these two sets of grid wires are secured to end

rings 18 and 19 by means of binding wires 55 wound around these rings. Supporting arms 20 are secured to these two rings and together with the rings form a rigid support for the grid. These supporting arms and the end rings preferably are made of tungsten or similar metal from which the occluded gas may easily be removed so there is no tendency for the evolution of gas when the parts are heated during the normal operation of the device.

I have indicated in the drawing one convenient way of uniting the arms 20 with the rings 18 and 19. These rings are formed of a strip of metal 21 stamped out, as indicated in Fig. 4, with ears 22 projecting from 70 its edges. This strip of metal is bent into the form of a ring, these ears bent over and the arms 20 inserted through the holes 23 in the ears 22. The arm 20, which passes through the holes 23 at the ends of the strip 75 which comes opposite each other also serves to hold the two ends of the strip together. After the arms 20 are inserted in these holes the ears may be squeezed or bent in such a way as to firmly grip the arms 20 and thereby secure the parts together without the necessity of any welded or soldered joints. The grid structure described is supported in the desired position in the receptacle by means of a sleeve 24 which surrounds the re- 80 entrant tubular portion 12 and is securely fastened thereto by means of clamping screw 25. Supporting arms 26 are secured to this sleeve 24 and the members 20 which are of considerably smaller diameter than the dia- 85 meter of the arms 26 are fastened to the arms 26 in the manner indicated at 27 in Fig. 2. For convenience in the construction of the device the end of the portion 2 of the receptacle may be left open until the parts 90 have been sealed together and then closed by means of a cap 28 which is soldered to the receptacle or welded thereto to form an air-tight joint.

In the operation of the device described 100 for the control of large energies, the anode 2 should be artificially cooled. This may be accomplished by placing it in a bath of water or other suitable cooling liquid and providing means to insure good circulation 105 of the cooling liquid. In view of the fact, therefore, that the anode 2 will normally operate at a low temperature, it is possible

to make use of metal for its construction having a comparatively low melting point. I have found that copper is very suitable for this purpose.

5 In the exhaustion of the device described, to remove all air as well as all the gases occluded in the metal parts, I prefer as a preliminary step to heat the anode 2 by means of heat radiated from the cathode 5. 10 It is possible to heat the anode to red heat in this way and thereby drive off a large portion of the occluded gases. After the exhaustion has been carried on in this way until the evolution of gas is greatly decreased or substantially stopped, a source of 15 potential is connected between cathode and anode so that the anode will be bombarded by electrons emitted from the cathode. At this point in the exhaust the cooling medium 20 is applied to the anode to protect it from overheating and the gas removed during this stage is therefore removed principally as a result of bombardment. Occluded gas is also removed from the grid structure by 25 bombarding the grid and its supporting parts by electrons given off from the cathode.

What I claim as new and desire to secure by Letters Patent of the United States is:—

1. The method of removing occluded gas 30 during the exhaustion of an electron discharge device comprising a filamentary cathode adapted to be heated to incandescence and an anode, which consists in first heating the anode, by heat radiated from the 35 cathode, to a temperature sufficiently high

to drive off a large portion of the occluded gas in the metal parts of the device, and then bombarding the anode by means of electrons emitted from the cathode.

2. The method of removing occluded gas 40 during the exhaustion of an electron discharge device comprising a cathode adapted to be heated to incandescence and an anode, which consists in first heating the anode by heat radiated from the cathode, then bom- 45 barding the anode by means of electrons emitted from the cathode and maintaining the anode at an appreciably lower temperature during the second step than during the 50 first.

3. The method of removing occluded gas during the exhaustion of an electron discharge device comprising a cathode adapted to be heated to incandescence and an anode which consists in first heating the anode by 55 heat radiated from the cathode, then bom- barding the anode by means of electrons emitted from the cathode and simultaneously supplying a cooling medium to the anode.

4. The method of removing occluded gas 60 during the exhaustion of an electron discharge device including a cathode and an anode, which comprises heating the anode to a red heat by means of heat radiated from the cathode, and then bombarding the anode 65 by means of electrons emitted from the cathode.

In witness whereof, I have hereunto set my hand this 17th day of September, 1923.

HENRY J. NOLTE.
